DIRECTIONAL SIGN

Milton Immermann, Piermont, N.Y., assignor to The Hopp Press, Inc., New York, N.Y., a corporation of New York

Filed Apr. 16, 1959, Ser. No. 55,541

Term of patent 14 years

(Cl. D1—12)

FIG. 1

FIG. 2

Fig. 1 is a perspective view of a directional sign showing my new design; and

Fig. 2 is a top plan view thereof.

The other half of the sign not shown is substantially like the half shown.

The dominant features of my design reside in the portions shown in full lines.

I claim:

The ornamental design for a directional sign, as shown and described.
